US00D567508S

(12) **United States Design Patent** (10) Patent No.: **US D567,508 S**
Burney (45) Date of Patent: **** Apr. 29, 2008**

(54) **CUTICLE CLEANING DEVICE**

(76) Inventor: **Charles L. Burney**, 3022 Bayside Dr., Apt. E, Indianapolic, IN (US) 46214

(**) Term: **14 Years**

(21) Appl. No.: **29/288,392**

(22) Filed: **Jun. 8, 2007**

(51) LOC (8) Cl. **04-02**

(52) U.S. Cl. **D4/116**

(58) Field of Classification Search **D4/116, D4/130, 199; D28/63; D32/47; 15/159.1, 15/160, 161, 167.3, 186, 187; 4/605, 606; 211/65; 248/110, 206.2, 206.3, 683, 688**

See application file for complete search history.
